UNITED STATES PATENT OFFICE

HARRY D. BELL, OF NEW YORK, N. Y.

TOOTHBRUSH

Application filed January 9, 1932. Serial No. 585,681.

This invention relates to improvements in tooth brushes and has particular reference to tooth brushes in which the bristle support may be readily removed from the tooth brush so that the tooth brush may be made and sold in two pieces, one portion being the bristle supporting element or head and the other element being the handle.

A main object of the invention is to provide simple, strong, durable and economically manufactured elements provided with automatically latching and unlatching means whereby they can be readily assembled together as a complete tooth brush and readily disassembled when new bristles or new bristle supporting elements are to be employed.

A further object of the invention is to provide such a construction of latching and engaging elements cooperating with the head and the handle as will permit the quick and easy assembly of it, and yet be capable of being manufactured at low cost, while at the same time being strong, durable, sanitary and not objectionable in appearance.

Further and more specific objects, features and advantages will more clearly appear from a consideration of the specification hereinafter taken in connection with the accompanying drawing which forms part of the specification and which illustrates a present preferred form of the invention.

Briefly described the invention in its present preferred form comprises a handle element, a bristle supporting element provided with aligned adjacent bores and overlapping flanges or lip portions with interlocking means on said overlapping flanges to latch the elements together when they are brought into their cooperative relation and further combined with a metallic stem or connecting member projecting from one element to the other and lying in said bores.

In further particulars the invention includes overlapping flanges having preferably sloping interlocking faces and shoulders and cooperating interlocking tongues and grooves to prevent longitudinal and angular displacement together with the connecting metallic stem snugly disposed in the aligned bores to give the unit substantial rigidity.

The preferred present form of the invention is illustrated in the drawing, of which:

Fig. 1 is a side elevation of the brush;

Fig. 2 is a similar view showing the parts separated;

Fig. 3 is an enlarged partial longitudinal vertical section through the joint;

Fig. 4 is an inverted plan view of the bristle supporting element;

Fig. 5 is a plan view of the handle element as seen in Fig. 2; and

Fig. 6 is a cross-section taken on the line 6—6 of Fig. 3.

As shown in the drawing, the preferred form of the invention comprises a handle element 10, an element 11 supporting bristles 12. These two elements are provided with aligned bores 13 and 14 adapted to receive a metal stem therein when the parts are joined together as shown in Fig. 3, this stem acting as a connecting element to add rigidity to the device.

Preferably the portion of the stem 15 extending into the bore in the handle 10 is provided with notches 16 into which the material of the handle is imbedded to firmly hold the stem onto the handle portion. It is understood, of course, that this stem instead of being imbedded at one end of the handle portion may be imbedded or molded into the bristle supporting portion, as an alternative, as desired. It will be seen that the handle portion has a projecting flange or lip 17 preferably provided with a raised transverse tongue 18 which is preferably molded integral on the flange 17. It will also be noted that the forward face of the flange 17 is tapered or sloped as at 19. This tapering or sloping surface 19 is adapted to abut a similarly sloped shoulder 20 on the bristle supporting element 11.

The bristle supporting element 11 is provided with a projecting flange or lip 21 which is preferably provided with a transverse groove 22 adapted to cooperate with the tongue 18 when the parts are placed together. The forward end of the flange 21 is provided with a sloping face 23 adapted to cooperate and abut a similarly sloped shoulder 24 on the handle portion 10. These flanges or lips 17

and 21 are also provided with longitudinal grooves 25 and 26 in line with the bores 13 and 14 to snugly receive the stem 15.

In the manufacture of the device the handle 10 and the bristle supporting element 11 are preferably molded to the form shown in the figures, but the bores 13 and 14 are preferably drilled therein. The stem 15 is then preferably firmly inserted in the handle portion 10. With the parts in the position shown in Fig. 2, the elements are moved together with the free end of the stem 15 entering the bore in the bristle supporting element 11. As the flanges are brought into their abutting relation the lip 21 will slip over the lip 17 until the groove 22 and the tongue 18 overly each other whereupon these lips will snap together and lock.

This device is exceedingly simple to manufacture, is compact, and durable, and when the parts are assembled the appearance is that of an integral one-piece brush. To separate the parts it is merely necessary to exert a steady longitudinal pull whereupon the lips are disengaged and in a similar manner to connect the elements it is merely necessary to introduce the free end of the stem into the corresponding bore and exert a steady force to press the parts together. When the parts reach their ultimate cooperative position they will snap firmly together. The sloping shoulders and faces of the flanges on the elements 10 and 11 cooperate to assist in preventing any relative angular displacement of the parts. The tongue 18 and the groove 22 assist in preventing longitudinal displacement of the parts. The stem 15 assists in keeping the parts aligned and making and keeping the unit strengthened and substantially rigid while in use. It is, of course, to be understood that the slope of the shoulders and faces described above may be changed in degree or direction, if desired. It is also understood that these faces and shoulders may be disposed vertically without any slope, if desired. It is also obvious that the position of the tongue 18 and the groove 22 may be reversed without disturbing the inventive concept and the effective cooperation of the parts. The device is extremely simple, compact and durable; it is very easy to assemble and disassemble; and affords a strong, efficient tooth brush for which replaceable bristle supporting elements may be bought at low cost, repeatedly, to cooperate with the same handle element.

While the invention has been described in detail and with respect to a present preferred form thereof it is not to be limited to such details and forms since many changes and modifications may be made in the invention without departing from the spirit and scope of the invention in its broadest aspects. Hence it is desired to cover any and all forms and modifications of the invention which may

come within the language or scope of the appended claim.

What is claimed, is:

A tooth brush comprising a handle element, a separable bristle supporting element, 70 said elements having aligned bores in adjacent ends, a stem lying snugly in said bores and acting to connect said elements, integral overlapping flanges formed on adjacent ends 75 of said elements, interlocking means on said flanges to hold the elements together when disposed in abutting relation, said flanges and said elements formed with cooperating sloping faces and shoulders adapted to lie in abutting relation when the elements are 80 drawn together to prevent relative angular movement between the elements.

Signed at New York in the county of New York and State of New York, this 8th day of January A. D. 1932.
